UNITED STATES PATENT OFFICE

WILLIAM H. GERSTENSLAGER, OF AKRON, OHIO, ASSIGNOR TO THE GOODYEAR TIRE & RUBBER COMPANY, OF AKRON, OHIO, A CORPORATION OF OHIO

MACHINE EMPLOYED IN MANUFACTURING BELTS

Application filed January 3, 1929; Serial No. 330,033.

This invention relates to machines for manufacturing endless rubber belts and it has particular relation to a machine for separating cores of the belts previous to the process steps of applying a cover thereto and subsequently vulcanizing them.

An object of the invention is to provide a machine which will be capable automatically of separating adhering cores of rubber belts, following the cutting thereof from an elongate cylindrical band of rubberized material.

An ordinary method of manufacturing endless belts composed of rubberized material involves the spiral winding of strips of the rubberized fabric material upon a collapsible drum until a predetermined thickness thereof is obtained and thereafter cutting through the cylindrical band, thus forming it into narrow annular cores. The cores, however, do not remain separated but spring back into engaging and adhering relation, owing to the resiliency of the rubber, the adhesive properties thereof, when in an unvulcanized state, and the fact that the inner peripheral surface of the band firmly engages the drum and prevents relative sliding movement between the cores as the cutting knife is projected through the band. Hence, after the drum is collapsed and the band of adhering cores bodily removed therefrom, it is necessary forcibly to separate the cores. Heretofore, the cores have been separated by pulling them apart manually.

This invention involves a machine for separating the cores automatically following their removal from the collapsible drum. It embodies a pivoted arm having rollers on its upper surface for supporting the assembled band of cores and a removable chain adjacent the free end of the arm, provided with hooks for engaging successively the end cores and separating them from the remaining ones. After each core is separated from the band, another means threads it onto a rod from whence the collected cores finally are removed for the subsequent steps of being covered with fabric and vulcanized.

For a better understanding of the invention, reference may now be had to the ac-

companying drawings, forming a part of the specification, in which:

Fig. 1 is a side elevational view of a machine constructed according to one embodiment of the invention;

Fig. 2 is a plan view of the machine shown by Fig. 1;

Fig. 3 is a cross-sectional view taken substantially along the line III—III of Fig. 1;

Fig. 4 is a cross-sectional view taken substantially along the line IV—IV of Fig. 2;

Fig. 5 is a cross-sectional view taken substantially along the line V—V of Fig. 2;

Fig. 6 is a cross-sectional view taken substantially along the line VI—VI of Fig. 1;

Fig. 7 is an enlarged view of a portion of a chain employed in the machine, illustrating the construction of a hook secured thereto;

Fig. 8 is a view taken from the left side of Fig. 7, with portions of the structure omitted for the purpose of clearness; and

Fig. 9 is a cross-sectional view taken substantially along the line IX—IX of Fig. 1.

Referring to Figs. 1 and 2, a frame 10 comprises four vertically extending angle bars 11, 12, 13 and 14 riveted at their upper ends to vertically disposed angle plates 22, which plates in turn are riveted to the corners of a rectangular frame composed of horizontally disposed angle bars 17, 18, 19 and 20. The vertically disposed angle bars 11 and 14 are connected by oppositely inclined bracing bars 25 and 26 riveted respectively to the opposite ends of the former, with the latter projecting across each other intermediate their ends and riveted together as indicated at 27. Similarly, the vertically disposed angle bars 13 and 14 are interconnected by bracing bars 29 and 30 riveted thereto and which, intermediate their ends, are riveted together as indicated at 31. In turn, the vertically disposed angle bars 12 and 13 are connected by bracing bars 35 and 36 secured together intermediate their ends by a rivet 37.

A bearing bracket 35 is secured by bolts 36 to the upper end of the angle bar 11 and one of the plates 22. The bracket is provided with a laterally offset, vertically projecting trunnion 38, which is received within

55

a bearing 44 having a bearing bracket 40 formed integrally therewith. Bolts 42 projecting through the bracket 40, secure the latter rigidly to one end of an arm 43 which is substantially of the same length as the horizontally disposed angle bars 17 and 19 and, in its normally operative position, is disposed parallel thereto. The arm 43 is releasably retained in position by a latch 48 having a notch 57 at one end in its lower edge, adapted to engage the upper edge of the arm. At the opposite end, the latch is pivotally connected by a bolt 49 to an obliquely projecting portion 50 of an angle bracket 52 riveted at its base to the angle bar 17, as indicated at 53.

A plurality of rollers 60, disposed on opposite sides of the arm 43 and having substantially semi-ellipsoidal outer surfaces and 20 plane inner surfaces are rotatably mounted on stud bolts 61 projecting through the rollers and the arm. The arm 43, at its outer end, also supports a pair of vertically disposed bars 63 and 64 (Fig. 9) secured thereto by 25 screws 59, which terminate adjacent the upper edge of the arm but project below its lower edge. The lower ends of the last mentioned bars rotatably support a pulley 88 therebetween whereas an arcuate plate 62 rigidly secured to the arm 43, is disposed in overlapping relation to the upper ends thereof. The curvature of this plate is similar to that of the rollers 60 and its upper surface is disposed substantially in the plane of the upper 30 surfaces thereof.

The opposite sides of the arm 43 below the rollers 60, are provided with longitudinally extending grooves 65 and 66, extending from a point adjacent the pivoted end of the arm 40 to the free end thereof. The grooves are adapted to retain a cross-head 68 slidably on the arm. This crosshead comprises a bar 69 disposed transversely of the arm 43, having a central groove 72 in its upper surface extending normally to its length and a central portion 70 projecting rearwardly from the bar. The central portion 70 also is provided with a groove similar to the groove 72 and communicating therewith. These grooves in the bar 69 and portion 70 receive the lower edge of the arm 43 while a pair of flanges 75 and 76, projecting inwardly from the upper edges of the grooves on opposite sides thereof, are disposed within the aforesaid grooves 65 and 66 in the arm, thus retaining the crosshead thereon. In addition, the groove 72 on the outer side of the bar 69 is enlarged (see Fig. 4) sufficiently as indicated at 71 to receive the bars 63 and 64 on the outer 50 end of the arm 43 when the crosshead is at this end of the latter. The crosshead 68 is releasably retained adjacent the pivoted end of the arm 43 by a thin latch bar 78, secured by screws 80 and 81 at one end to the portion 70 of the crosshead and having a lip 82 at its

other end adapted to engage resiliently a bar 83 projecting downwardly from and secured by a bolt 84 to the arm.

A semi-circular bar 92, disposed above the crosshead 68 and provided with laterally projecting portions 93 and 94 at its ends, secured by screws 95 and 96 to opposite ends of the bar 69, extends over the arm 43 on the opposite sides thereof and above the rollers 60. This bar, on its inner periphery, is provided with hooks 97 and 98, projecting laterally from the side thereof next to the free end of the arm 43 and thereafter upwardly, whereby a band of belt cores encircling the arm 43 may be engaged at one end by the crosshead. When the crosshead 68 is in its extreme outer position on the arms 43, and the bars 63 and 64 are disposed in the enlarged portion 71 of the groove 72, the semi-circular bar 92 is spaced from the end 55 of the arm 43 a distance substantially equal to the width of a single belt core.

In addition, the portion 70 of the crosshead (see Fig. 1) is provided with a depending apertured lug 90, to which one end of a cable 91 is attached. The cable extends toward the outer end of the arm 43 and is trained over the aforesaid grooved pulley 88 which is rotatably mounted between the lower ends of the bars 63 and 64, thence in a 50 reverse direction to a point adjacent the latch rod 48 where it is trained over a grooved pulley 100 rotatably supported on the lower end of a bar 101 secured by screws 102 to the arm. Thereafter, the cable extends downwardly and under a grooved pulley 105 rotatably mounted in a fork 106 secured to a counter-weight 107, from whence it extends upwardly and is secured at its other end to a lug 108 integral with the lower edge of the 100 arm 43.

A motor 115, mounted on a plate 116 secured by rivets 117 to the upper surface of the angle bars 17, 18 and 19, is provided with a shaft 118 connected by a coupling 119 to a stud 110 shaft 120 forming part of a reduction gearing 121. A second stud shaft 122 projecting from and operatively connected to the reduction gearing 121, in turn is connected by a coupling 123 to a shaft 124 journaled in bearing brackets 130 and 131 bolted to the plate 116 as indicated at 132 and 133. The latter shaft projects at right angles to the angle bar 17 and has an extended end provided with a sprocket wheel 136 which is disposed adjacent the end of the arm 43 in substantially the same plane thereof when it is in its operative or latched position. A chain 140 trained over the sprocket wheel 136 also is trained over a sprocket wheel 142 rigidly secured on one end of a shaft 143 journaled in bearing brackets 148 and 149, which brackets are secured by bolts 150 to other brackets 151 and 152 in turn, respectively secured by bolts 155 and 154 to the vertically extending 125 130

angle bars 12 and 13 adjacent their lower ends.

The chain 140 is provided with a plurality of hooks and, as best shown by Figs. 7 and 8, each of the hooks comprises a relatively wide plate 160 disposed parallel thereto and secured by screws 161 to projections 162 on opposite sides of certain links of the chain. At one end, the plate 160 converges into a portion 165 of less width than the major portion of the plate and centrally disposed relative thereto, which portion projects in a normal direction outwardly from the plate. A hook portion 166 integral with the outer end of the portion 165, extends parallel to but away from the plate 160, and is sharpened at its outer end, as indicated at 167.

Bars 170 and 171, pivoted intermediate their ends on opposite ends of a pin 172 disposed adjacent each hook and forming part of the chain, have extended portions 173 and 174 disposed on opposite sides of the hook portion 166 and the portion 165 of the plate 160, which extended portions are connected by springs 180 and 181 to the plate 160, certain of the screws 161 serving to secure the upper ends of the springs thereon. Normally the portions 173 and 174 of the bars 170 and 171 are disposed inwardly of the end of the hook 166 but are adapted to be moved against the action of the springs 180 and 181 past the end thereof by a pin 185 disposed in the path of movement of the other ends, indicated at 176 and 177, of the bars 170 and 171, which extend oppositely to the ends 173 and 174. This pin is mounted on the upper end of a bar 186 adjustably secured by a bolt 191 to the upper end of a bracket 190, which bolt projects through the lower end of the bar and through an elongated slot 189 in the bracket. The latter bracket is secured by one of the bolts 150 to the aforesaid bracket 152.

A switch 195, having a pivoted operating arm 196, is secured by a screw 197 to a bracket 198 which in turn is also secured by the last mentioned bolt 150 to the bearing bracket 149. This switch is in the circuit of the motor 115 and when the arm 196 is in its inoperative position energization of the motor is prevented.

A pinion 200 (Fig. 2) rigidly secured to the shaft 143 between the bearing brackets 148 and 149 and adjacent the former, has a chain 201 trained thereover, which chain in turn extends over a pinion 202 rigidly secured on a second shaft 205 adjacent the opposite end of the frame 10. The latter shaft is rotatably mounted in bearing brackets 206 and 207 secured by bolts 208 and 209 to other brackets 210 and 211 bolted to the vertically extending angle bars 11 and 14, as indicated at 212. One end of the shaft 205, extending beneath the arm 43, has a bevel gear 215 on its end meshing with a bevel gear 216 secured to a

shaft 225 rotatably supported in a bearing bracket 217, which bracket is secured by bolts 218 to the bracket 211. The shaft 225 extends at a slight angle to the vertical in the vertical plane of the arm 43 to a point adjacent the chain 140 and is provided with a sleeve 226, having a disc portion 228 secured by a set screw 227 thereon. In addition, the shaft 225 is provided with a thread 230 outwardly of the sleeves 226.

The plate 116 also supports an angle bracket 265 having a base 268 secured by bolts 267 to the plate and a vertically projecting portion 269 to which an arm 263 is secured by bolts 264. This arm extends transversely of the plane of the arm 43 adjacent the free end of the latter and is disposed vertically above both the sprocket wheel 136 and the curved bar 92 on the crosshead 68. Spaced bars 260 and 261, secured by bolts 262 to the arm 263, extend downwardly on opposite sides of the vertical plane of the arm 43 in positions closely adjacent to the free end of the latter. These bars are also disposed adjacent the sprocket wheel 136, so that when the hooks 90 on the chain 140 move downwardly over the sprocket wheel, they pass between the bars.

In operation of the above-described mechanism, a band 250, composed of individual belt cores 251 adhering together owing to the adhesive qualities of the unvulcanized rubber therein, is disposed over the arm 43 with the latter in its unlatched position and the inner end core is fastened to the hooks 97 and 98. Thereafter, the arm is moved about the pivot 38 into its latched or operative position. With the band 250 in this position, release of the latch 78 and thereby the crosshead 68, results in the counterweight 107 urging the bar 92 of the crosshead against the end of the band hooked thereon. This, in turn, urges the opposite end of the band against the aforesaid bars 260 and 261 mounted on the arm 263 adjacent the free end of the arm 43, which bars are spaced sufficiently from the end of the arm 43 that with the band in this position, the outer end core is clear of the end of the arm. Energization of the motor 115 now causes movement of the chain 140 in the direction indicated by the arrow in Fig. 1 and as one of the hooks 166 moves past the end of the band 250, it engages the core which is beyond the end of the arm 43 and pulls it downwardly, thus separating it from the band as shown by Fig. 1. As soon as the core is separated from the upper part of the band, the counterweight 107 moves the crosshead 68 and hence the band 250, until the next core is moved into abutting relation with the bars 260 and 261. After the first mentioned core is completely separated from the band, its upper end falls upon the outer end of the rod 225 which also is being turned by the motor 115.

Further movement of the hook causes the

arms 170 and 171 to be engaged by the pin 185 and hence the portions 173 and 174 of the arms to move past the hook and disengage the core therefrom. Owing to the fact that the 6 shaft 225 is rotating, the core is moved downwardly thereon by the thread 230. In this manner all of the cores 251 may be completely separated and all but the last core, which rests on the hooks 97 and 98, loosely assembled 10 on the shaft 225 whereafter they may be removed. If, for any reason however, one of the cores should not be disengaged from a hook on the chain 140 and it should be carried past the rod 225, subsequently it will be 15 moved against the arm 196 of the switch 195 thereby operating the latter and opening the circuit to the motor 115.

From the above description, it is apparent 20 that a machine has been provided for separating automatically the cores of rubber belts which adhere to one another, following the cutting thereof from a band of assembled rubberized material. It is apparent that the machine is simple and that no manual operation 25 is required other than disposing the band of assembled cores in the machine and removing the separated cores therefrom.

It also is apparent that the machine is 30 adapted for separating articles of various shapes, such as bales of rubber for example. The arm 43 obviously may be adapted to support articles having a shape other than cylindrical.

Although I have illustrated only the preferred form which my invention may assume 35 and have described that form in detail, it will be apparent to those skilled in the art that the invention is not so limited but that various modifications may be made therein without departing from the spirit of the invention or from the scope of the appended claims. 40

What I claim is:

1. Apparatus for disassembling circular 45 articles from each other comprising a frame, an arm pivoted on the frame adapted to extend through the circular articles to be separated, rollers on the arm adapted to support the articles to be disassembled, automatic means for periodically moving the articles toward the free end of the arm, and means adapted to engage the articles periodically and disassemble them. 50

2. The combination of a frame, rollers, on the frame adapted to support an article to 55 be disassembled, automatic means independent of the rollers for periodically moving the article toward one end of the frame, and means adapted to engage the article periodically and disassemble it by increments. 60

3. The combination of a frame, an arm on the frame adapted to project through a cylindrical band of rubber cores adhering together, means for periodically moving the band towards an end of the arm, means for 65 successively separating an end core from the

others, and other means for threading the cores on a rod following the separating operation.

4. The combination with a frame, an arm on the frame adapted to project through a 70 cylindrical band of rubber cores adhering together, means for periodically moving the band towards an end of the arm, means limiting the movement of the band to such position that one of the cores is disposed beyond 75 the end of the arm, means for successively separating the end core from the others, and other means for threading the cores on a rod following the separating operation. 80

5. In a belt manufacturing device, means for supporting a cylindrical band of rings adhering one to another, means for removing the rings one at a time from the band, and means operating in conjunction with the removing means for threading the rings upon 85 a support after such disassembling operation.

In witness whereof, I have hereunto signed my name.

Signed at Akron, in the county of Summit and State of Ohio, U. S. A., this 2nd day of 90 January, 1929.

WILLIAM H. GERSTENSLAGER.
